WRAPPING MACHINE

Henry J. Werden, West St. Paul, and Francis Werden, St. Paul, Minn., assignors to American Machine & Foundry Company, a corporation of New Jersey

Application August 2, 1940, Serial No. 349,924

15 Claims.

(Cl. 93—2)

This invention relates to improvements in wrapping machines, more particularly to bread wrapping machines of the type shown in the patents issued to T. Jensen, Patent No. 2,320,362, June 1, 1943, and 2,221,481, November 12, 1940, which are provided with a conveyor having sets of flights arranged to admit loaves of bread therebetween from a chute, or from an infeed conveyor delivering sliced loaves from a slicing machine, and advance the loaves endwise into position to be ejected from between the conveyor flights on to a lifter table provided with tuckers acting to tuck the ends of a wrapper enfolded about the loaf during the delivery of the same to the table and moving upwardly with the table, whereby the tucked ends of the package are engaged with folder structure acting to fold the wrapper ends over said tucked portions. An object of the invention is to simultaneously adjust in machines of the general type shown in the above-mentioned applications, the gap between the conveyor flights, the tuckers and the folders to accommodate loaves of various lengths.

Another object is to adjust the breadth of the pusher which ejects the loaf from between the conveyor flights, in accordance with the increased or decreased length of the particular run of loaves being handled, simultaneously with the adjustment of the conveyor flights, tuckers and folders. A further object is to adjust the guide which is disposed along the path of the conveyor flights in engagement with the inserted loaves, and extends into the proximity of the path of the pusher, so that the guide will be advanced or retracted in accordance with the expansion or contraction of the pusher, simultaneously with the adjustment of the conveyor flights, tuckers and folders.

Still another object of the invention is to tilt the leading flight of each set of conveyor flights forwardly at the loaf-inserting position to facilitate insertion of the loaf. Heretofore the flights have been set to closely fit the inserted loaves, wherefore the proper insertion of the loaves was rendered difficult by disalignment of the conveyor flights with the infeed chute or conveyor due to improper setting of the conveyor flights, or other causes.

Heretofore the loaves were advanced into the path of the pusher against a stop plate; and with sliced loaves the heel at the leading end of the loaf would enter the space provided in the stop plate for passage of the flights, wherefore this heel of the loaf occasionally would not be ejected by the pusher. Accordingly, a further object of

the invention is to provide flights having a sufficient breadth to permit elimination of the stop plate. Thus the flights will extend in sufficient proximity to the tuckers to guide the loaf during ejection. Moreover the ejecting pusher is provided with projections extending sufficiently into slots on the interior faces of the flights to assure ejection of the heels with the rest of the loaf by the pusher, and the provision of structure for this purpose constitutes another object of the invention.

A further object of the invention is to provide an independent manual adjustment for the tuckers and folders. Such adjustment of the tuckers is desirable when changing over from the wrapping of bread loaves to cartons.

With these and other objects not specifically mentioned in view the invention consists in certain constructions and combinations hereinafter 15 fully described and then specifically set forth in the claims hereunto appended.

In the accompanying drawings which illustrate an embodiment of the invention and form a part of this specification and in which like 20 characters designate similar parts:

Fig. 1 is a plan view of a wrapping machine exemplifying the invention;

Fig. 2 is a detail plan view on an enlarged scale of the adjustable pusher mechanism;

Fig. 3 is a detail side elevation on the same enlarged scale as Fig. 4, showing the conveyor and sprocket adjusting mechanism as viewed from line 3—3 of Fig. 4;

Fig. 4 is a partial rear elevation of the machine showing the manner in which the sprocket adjusting mechanism is supported on the rear frame, as viewed from line 4—4 of Fig. 1;

Fig. 5 is a fragmentary longitudinal section of the sprocket adjusting mechanism taken on the line 5—5 of Fig. 6;

Fig. 6 is a cross-section taken on line 6—6 of Fig. 5;

Fig. 7 is a detail longitudinal section taken on line 7—7 of Fig. 5;

Fig. 8 is a detail view of the tucker adjusting mechanism;

Fig. 9 is a sectional view on line 9—9 of Fig. 8;

Fig. 10 is a detail view of the mechanism for disengaging the tucker adjusting means from the main control;

Fig. 11 is a detail plan view taken from the line 11—11 of Fig. 3, of the portion of the machine shown in Fig. 3, the pusher being shown fragmentarily; and

Fig. 12 is a front elevation of the machine.

Referring to Figs. 1 and 12, it will be seen that the conveyor, pusher, tuckers, top folders, plough folders, bottom folders, heat sealers and refrigerated coolers are simultaneously adjustable to accommodate loaves of various lengths. For this purpose a hand wheel 10 is mounted on a shaft 12 supported by the side frames 112 and having right and left-hand threaded portions 14 and 16 threaded into brackets 18 carrying frames 20 on which are mounted the top folders 22, plough folders 24, bottom folders 26 and heat sealers 28. The construction of these folders and sealers may be similar to that shown in the co-pending application of T. Jensen, on which Patent No. 2,320,362 was granted, to which reference may be had for the details thereof. A sprocket 30 on shaft 12 is connected by sprocket chain 32 to a sprocket 34 on a shaft 36 having right and left-hand threaded portions threaded into lugs 38 at one end of the refrigerated coolers 40, and shaft 36 is provided with a sprocket 39 connected by a chain 42 to a shaft (not shown) similarly threaded into lugs at the other end of the coolers. Thus upon turning the hand wheel 10 the coolers will be adjusted simultaneously with the folders and sealers. The construction of the coolers may be similar to that shown in the above mentioned Jensen application, S. N. 225,697, on which Patent No. 2,320,362 was granted.

Referring to Fig. 2, it will be seen that the pusher is formed with a pusher head 101 fastened on a slide 102 which is supported from lugs 104 to which are fastened the ends of a bar 105 entering a key-way in the side of the slide, the slide being retained on the bar by plates 106 fastened to the lugs 104 and the latter being carried by the bar 108 fastened on the tie-rods 110 connecting the frames 112. Extensions 114 and 116 of the pusher head 101 are slidably mounted on the latter, extension 114 being provided with lugs 118 and 120 projecting inwardly into slots 122 and 124 formed in the front and top face respectively of the pusher head. The extension 116 slides upon a flange 125 formed on the front face of the pusher head, the flange being of sufficient thickness and breadth to snugly fit the extension 114. The latter is formed to telescope on the extension 114 when these two parts are adjusted inwardly on the pusher head to diminish the effective breadth of the latter. For adjustment of the extensions toward and away from each other there are provided arms 126 and 128 which are equipped with lugs or projections 127 and 129 respectively and fastened to the extensions 114 and 116 respectively and loosely mounted on a cross-bar 130 clamped in a bracket 132, which may be welded or suitably fastened to the bottom of the slide 102. In the bracket 132 is journaled the sleeve 134 within which is fastened the mid-section of a screw having right and left-hand threaded portions 136 and 138, respectively, threaded into lugs 140 and 142 of the arms 126 and 128. On sleeve 134 is fastened a gear 144 meshing with a gear 146 mounted on one end of the shaft 148. The latter is journaled in the bracket 132, and on its other end is mounted a universal joint 150 connected to a link 152 telescoping into a tube 154 connected to another universal joint 156 suitably rotated by suitable mechanism hereinafter described. Thus the extensions may be moved toward and away from each other to increase or diminish the effective breadth of the pusher in accordance with variations in the lengths of the loaves to be handled. It may be noted that the

front end of the arm 126 is provided with a ledge 158 of the proper thickness to form a face flush with the front face of the extension 116 when the extensions are brought together for the minimum effective breadth of the pusher, this feature being desirable when wrapping cartons. The slide 102 is connected by a link 160 to an arm 162 mounted on a shaft 164 and actuated by a link 166 from a cam (not shown).

10 A bevel gear 50 on shaft 12 meshes with a bevel gear 51 on a shaft 52 supported by the front side frame 112 and connected by a universal joint 54 to a link 56 carrying a second universal joint 58 which is fastened to a stub shaft 60 journaled in a housing 62. A bevel gear 64 fastened on shaft 60 meshes with a bevel gear 66 fastened on the end of a spindle 68 projecting into the housing 62 (Figs. 8 and 12). Spindle 68 has a right hand threaded portion threaded into a tucker-supporting arm 70 on which is fastened a tucker 72. The arm 70 is free to slide to and fro on a bracket 74 whereby turning of the shaft 68 will adjust the tucker 72 inwardly or outwardly. The end of the shaft 68 projecting from the bracket 74 has a squared cross-section slidably fitting a tube 76 fastened to the end of a spindle 78 having a left-hand threaded portion threaded into a tucker-supporting arm 80, carrying the other tucker 82. The arm 80 is free to slide on bracket 83 and is guided thereon by guides 84 and 85 fastened to the arm and extending under the bottom of the bracket (Fig. 9). The bracket 83 is clamped by bolts 86 to the support 87 which is slidably mounted on a shaft 88 and moved outwardly during the delivery of the loaf to the lifter by the action of a roller 89 engaging a plate 90 on the support 87. The roller is mounted on a swinging block 91 loosely mounted on shaft 88 and rocked back and forth by a link 92 from a cam (not shown) to move the support outwardly with the tucker 82 during the delivery of the loaf to the lifter table, the plate 90 being held against roller 89 by a compression spring 93 bearing against support 87 and seated against a collar 94 fastened on shaft 88, whereby the tucker 82 will be returned to its inward position to tuck one end of the wrapper enwrapping the article delivered to the lifter table. The bracket 74 is similarly clamped to a support 95 similarly mounted on shaft 88 and provided with a plate 96 engaging a roller 97 on block 91 against which it is held by compression spring 98. The bevel gear 64 on shaft 60 is held in mesh with bevel gear 66 by a compression spring 99 seated against bracket 62 and bearing against a knob 100 on the projecting end of shaft 60. Thus upon pushing the knob inwardly the gears 62 and 66 will be disengaged and the tuckers may be manually adjusted, as is desirable when changing from wrapping bread to wrapping cartons, by turning the tube 76 by hand. With the illustrated tucker adjusting construction, which forms the subject matter of my divisional application, Serial No. 497,186, filed August 3, 1943, it is possible to have a greater range of adjustment without recourse to reversal of tuckers from one side of the tucker supporting arms to the other as heretofore for the minimum and maximum lengths of articles.

Referring to Fig. 3, it may be noted that a sprocket chain 202 driven from a sprocket 203 on the shaft 12 drives a sprocket 204 on a shaft 206 to which the universal joint 156 is fastened, said universal joint carrying the tube 154 which is connected to the universal joint 150 (Fig. 2) fastened to the pinion shaft 148 of the pusher

adjusting mechanism as described above. Shaft 206 is mounted in bearing lugs formed on a housing 207 and is also provided with a pinion 208 driving a gear 210 on a countershaft 212 also mounted in bearing lugs of housing 207. Shaft 212 carries a worm 214 which meshes with a worm wheel 216 mounted on a shaft 218 journaled in housing 207. On shaft 218 is mounted a pinion 220 meshing with a rack worm 222 mounted on a shaft 224 mounted in housing 207. A rack 226 is fastened at one end in the worm 222 and projects into a sleeve 230 on which are mounted sprockets 232 and 234 having abutting flanges which enclose the ends of a cross-shaft 236, projecting through sleeve 230 and bearings 238 in sleeve 230. A pinion 242 on shaft 236 meshes with the rack 226 whereby bevel gears 244 and 246 on the ends of shaft 236, which mesh with ring gears 248 and 250 fastened to the sprockets 232 and 234, respectively, may be rotated to turn the sprockets 232 and 234 in opposite directions simultaneously. The sprockets 232 and 234 are driven from a bevel gear 252 which is fastened to the sleeve 230 and intermittently driven from a suitable indexing mechanism (not shown), the sleeve being supported by a bearing 254. The housing 207 is provided with a downwardly extending flange which is fastened to the cross members 112a and 112b and upright 112c of the rear frame 112, as shown in Figs. 4 and 12. The bearing 254 may be formed integral with the cross member 112a, as shown in Fig. 4. The construction of the rear frame is the same as the front frame except for the additional cross members 112a and 112b which are connected to an upright 112c which is narrower than the corresponding upright of the front frame.

Sprocket 232 drives a sprocket chain 256 to which are fastened at equal intervals a series of brackets 258 each having fastened thereon a flight 262 (Fig. 3), the sprocket chain 256 running over an idler sprocket 257 loosely mounted on a shaft 261 supported by a bracket 263 mounted on the front frame 112 in the manner shown in Fig. 12. Sprocket 234 drives a chain 264 to which are fastened at equal intervals a series of brackets 266 on each of which is pivoted an arm 268 which is urged upwardly by a torsion spring 270, the chain 264 running over a sprocket 265 loosely mounted on shaft 261. Flights 272 are fastened to the upper end of each arm 268 in position opposing an adjacent flight 262 to clamp a loaf of bread therebetween. It may be noted that each torsion spring urges its respective flight 272 away from the opposing flight 262 of the other chain so that the loaf of bread may readily enter between them, which is particularly desirable with sliced loaves. The inner upper end of each arm 268 is suitably beveled and the lower end of each flight is disposed at an acute angle to the remainder of the flight, so that the extent which the flight 272 needs to be swung back to admit the loaf may be substantially reduced. Each inserted loaf is then advanced between a set of flights 262, 272, whereby the cam roller 274 on the lower end of the arm 268 rides along the inclined face of the cam rail 276 on to the bottom face thereof and swings the flight 272 against the adjacent end of the loaf to firmly clamp it against the flight 262 and maintains flight 272 in clamping position at the loaf-ejecting station. By the above described relative adjustment of the sprockets 232 and 234 various lengths of loaves may be accommodated, as the coacting flights of each set may be brought closer

together or farther apart within the desired range. Each flight has a bend in its mid-portion forming a slot adapted to receive the lugs or projections 127 and 129 of the pusher arms. These lugs project sufficiently into the slots to assure removal of the heels of sliced bread loaves.

The loaves are delivered from a chute (not shown), or from the delivery conveyor of a slicing machine, on to a runway 280 having a longitudinal slot through which the arms supporting the flights travel into loaf-receiving and ejecting positions successively. The loaves inserted between the flights are guided by a guide rail 282 engaging one side of the loaves. This guide is provided with strips 284 sliding between rollers 286, supported on uprights 288 and a tension spring 290 urges the guide forwardly toward the path of the pusher. A cable 292 is connected at one end to guide 282 and at the other end to a bar 294 fastened to one of the frames supporting the folders. The length of the cable is such that the rail 282 is maintained in a position slightly to one side of the path of the pusher and advanced toward or retracted from the same as the pusher is contracted or expanded to conform to different lengths of loaves.

While a set of flights is at loaf-ejecting position, the pusher advances and ejects the loaf on to a lifter table 296 which has hubs 298 fastened to shaft 88 at either side of block 91, shaft 88 carrying a cam lever (not shown) whereby shaft 88 is intermittently rocked to periodically raise the table from loaf-receiving position to a horizontal position aligned with a table 300. A web 35 of wrapping material (not shown) is fed into position to be partially enfolded about the loaf during its delivery to the lifter table, as described in the above-mentioned Jensen application, S. N. 225,697, and the tuckers are moved apart to admit the partially enfolded loaf therebetween and then moved inwardly to tuck the ends of the wrappers. During the ascent of the lifter table the top folders 22 fold the upper wrapper flaps over the tuckers. Then the loaf is advanced by flights (not shown) carried by a continuously traveling chain to advance the loaf upon table 300 whereby the final bottom flap is folded under the bottom of the loaf and the plough folders 24 and the bottom folders 26 complete the folding 50 of the ends of the wrapper. As the wrapped loaves are pushed through the sealers 28 and coolers 40, by the following loaves advanced over table 300, the finished loaves will be advanced beyond the coolers.

55. What is claimed is:

1. In a wrapping machine, the combination with a conveyor having sets of flights adapted to admit an article therebetween, of a member for ejecting articles from between successive sets of flights of said conveyor, and mechanism for simultaneously regulating the gap between the various sets of conveyor flights and the effective breadth of said member in accordance with various lengths of articles to be handled.

65. 2. In a wrapping machine, the combination with a conveyor having sets of flights adapted to admit an article therebetween, of a member for ejecting articles from between successive sets of flights of said conveyor, mechanism for simultaneously regulating the gap between the various sets of conveyor flights and the effective breadth of said member in accordance with various lengths of articles to be handled, and mechanism for delivering articles sidewise into successive 70 sets of flights of said conveyor.

3. In a wrapping machine, the combination with a conveyor having sets of flights adapted to admit an article therebetween, of a member for ejecting articles from between successive sets of flights of said conveyor, mechanism for simultaneously regulating the gap between the various sets of conveyor flights and the effective breadth of said member in accordance with various lengths of articles to be handled, and a guide disposed to engage a side of articles inserted between said sets of flights and extending into the proximity of the path of said member and connected to said mechanism for retraction into a position which will not interfere with the movement of said member when its breadth is being increased by said mechanism.

4. In a wrapping machine, the combination with a pair of spaced tuckers adapted to admit therebetween an article to be wrapped and engage the ends thereof, of an article feed for conveying articles in an endwise direction with respect to their length, said article feed including a pair of parallel endless members, and opposed grippers one on each member arranged to grip the ends of an article between them, means for supporting and intermittently driving said members to bring articles gripped between the opposed grippers into a predetermined position adjacent said tuckers, a device for ejecting articles from said feed at said predetermined position between said tuckers, and mechanism external to said endless members and the supporting and driving means therefor operable to vary the spacing of said grippers, without interrupting the movement of said members, and means operated by said mechanism for varying the spacing of said tuckers in conformity with variations in the spacing of said grippers.

5. In a wrapping machine, the combination with an article feed for conveying articles in an endwise direction with respect to their length, said article feed including a pair of opposed grippers arranged to grip the ends of an article between them, mechanism operable to vary the spacing of said grippers, spaced wrapping devices co-operating to act on opposite ends of the article, means for adjusting said devices toward and away from each other to fit different sizes of articles, and connections between said devices and said mechanism to simultaneously adjust the spacing between said grippers to correspond with the spacing of said devices as a result of the adjustment of the devices.

6. In a wrapping machine, the combination with a conveyor having sets of flights adapted to admit an article therebetween, of a member for ejecting articles from between successive sets of flights of said conveyor at a predetermined position of said flights to enfold the same in a wrapper disposed in front of said position, mechanism for simultaneously regulating the gap between the various sets of conveyor flights and the effective breadth of said member in accordance with various lengths of articles to be handled, sets of folders arranged to fold the ends of the wrapper inwardly over the ends of the article ejected from the conveyor flights, and means connecting said folders to said mechanism for adjustment of said folders simultaneously with said flights and member for accommodation of articles of various lengths.

7. The combination with a member for displacing articles, of mechanism for actuating said member, means for expanding and contracting said member to conform to various sizes of arti-

cles being handled, said member including a reciprocable slide, a pusher head mounted on said slide, extensions slidably mounted on said head at either end thereof, a screw carried by said slide and having a right-hand threaded portion threaded into one of said extensions and a left-hand threaded portion threaded into the other of said extensions, a gear fastened on said screw, a pinion meshing with said gear, a shaft carrying said pinion and mounted on said slide, a universal joint having one of its ends connected to said shaft, a link slidably mounted on the other end of said universal joint and adapted to turn said pinion shaft to vary the spacing of said extensions.

8. The combination with a member for displacing articles, of mechanism for actuating said member, means for expanding and contracting said member to conform to various sizes of articles being handled, and a guide arranged to guide an article into the path of said member and extending into the proximity of said path and connected to said means for retraction from said path or movement toward said path simultaneously with the expansion or contraction of said member by said means to compensate for various sizes of articles being handled.

9. The combination with a member for displacing articles, of mechanism for actuating said member, means for expanding and contracting said member to conform to various sizes of articles being handled, and a guide arranged to guide an article into the path of said member and extending into the proximity of said path and connected to said means for retraction from said path or movement toward said path simultaneously with the expansion or contraction of said member by said means to compensate for various sizes of articles being handled, said means including a spring urging the guide toward the path of said member, and a cable connected to said guide and adapted to retract it from said path.

10. In a wrapping machine, the combination with an article feed for conveying articles in an endwise direction with respect to their length, said article feed including a pair of opposed members arranged to grip the ends of an article inserted between them, and means for moving said members to a predetermined position, a pair of spaced tuckers adapted to admit therebetween and engage the ends of an article ejected transversely from between said members at said position and mechanism for simultaneously and correspondingly adjusting each of said members and tuckers toward and away from the opposed member and tucker respectively to accommodate therebetween articles of various lengths.

11. In a wrapping machine, the combination with spaced wrapping devices arranged to admit an article sidewise therebetween and fold a wrapper over the ends of the article inserted between them, means for delivering articles between said devices, said means comprising a pusher constructed and arranged so that its width may be varied to correspond to the length of the article to be wrapped, mechanism for adjusting said wrapping devices toward and away from each other to fit different lengths of articles, and instrumentalities interconnecting said wrapping devices and said pusher to automatically vary the width of said pusher in conformity with variations in the spacing of said wrapping devices produced by operation of said mechanism.

12. In a wrapping machine, the combination

with a pair of spaced tuckers adapted to admit therebetween an article to be wrapped and tuck a wrapper over the ends of the article, a member for delivering an article between said tuckers, said member having sections which are relatively adjustable to vary the effective breadth thereof, mechanism for adjusting said tuckers toward and away from each other to admit articles of various lengths therebetween, and connections between said tuckers and the adjustable sections of said member to vary the effective breadth of said member in conformity with variations in the spacing of said tuckers produced by operation of said mechanism.

13. In a wrapping machine, the combination with a pair of spaced tuckers adapted to admit therebetween an article to be wrapped and engage the ends thereof, of an article feed for conveying articles in an endwise direction with respect to their length, said article feed including a pair of endless members having parallel portions and series of grippers mounted on each of said members, each gripper on one of said members being arranged opposite a gripper on the other of said members along the parallel portions of said members to provide sets of grippers coacting along said parallel portions to grip the ends of an article inserted between a set of grippers, means for supporting and intermittently driving said members to advance articles gripped between each set of grippers to a predetermined position adjacent said tuckers, a device for ejecting articles from the set of grippers at said predetermined position into a position between said tuckers, mechanism external to said endless members and the supporting and driving means therefor to vary the spacing of grippers of each of the sets of grippers along said parallel portions of said members, said mechanism including a device for relatively moving said members to vary the spacing of each set of grippers to admit articles of different length, and means operated by said mechanism for varying the spacing of said tuckers in conformity with variations in the spacing of said grippers.

14. In a wrapping machine, the combination with an article feed for conveying articles in an endwise direction with respect to their length, said article feed including a pair of endless sprocket chains having parallel runs, series of conveyor flights on each of said chains, each flight on one of said chains being arranged opposite a flight on the other of said chains along said parallel runs to provide sets of grippers coacting along the parallel runs of said chains to

5 grip the ends of an article between them and advance the articles to a predetermined position, mechanism operable to move said chains relatively to each other to vary the spacing of the conveyor flights of each set of flights along said parallel runs to admit articles of different length, spaced wrapping devices arranged to admit articles therebetween after they are advanced to said predetermined position by said flights and cooperating to act on opposite ends of the article, means for adjusting said devices toward and away from each other to fit different sizes of articles, and connections between said devices and said mechanism to simultaneously adjust the spacing of the flights of said sets of conveyor flights, to correspond with the spacing of said devices as a result of the adjustment of the wrapping devices.

15. In a wrapping machine, the combination with an article feed for conveying articles in an endwise direction with respect to their length to 15 a predetermined position, said article feed including a pair of endless sprocket chains having parallel runs, series of conveyor flights on each of said chains, each of the conveyor flights on one of said chains being opposite one of the conveyor flights on the other of said chains along 20 said parallel runs to provide sets of flights coacting along said parallel runs to grip the ends of 25 an article between them and advance the articles along said parallel runs to a predetermined position, means for driving said chains to advance along said parallel runs to said predetermined position the articles gripped between the 30 sets of conveyor flights, a pair of spaced, opposed 35 tuckers adapted to admit therebetween and engage the ends of an article ejected transversely from between the set of conveyor flights at said predetermined position, and mechanism for simultaneously and correspondingly adjusting each 40 of said opposed conveyor flights and tuckers toward and away from the opposed conveyor flight and tucker respectively to accommodate therebetween articles of various lengths, said driving 45 means including a pair of sprockets over which said chains run, and said mechanism including a device for relatively rotating said sprockets to vary the spacing of the conveyor flights of each set of flights along said parallel runs, and instrumentalities operated by said device for simultaneously and correspondingly varying the spacing of said tuckers.

HENRY J. WERDEN.
FRANCIS WERDEN.
